MILL FOR DISPERSION AND MIXING

Marvin W. Ditto, New York, N. Y., assignor to
Gas Fuel Corporation, New York, N. Y., a
corporation of Delaware

Application July 12, 1938, Serial No. 218,883

21 Claims. (Cl. 259—9)

This invention relates to an oil aquolysis mill, that is a mill for incorporating water or the like into various substances.

One of the objects of the invention is to provide an improved mill for use in very high speed and high pressure work and where extremely fine dispersion is required.

Another object of the invention is to provide a novel mill available for all kinds of work requiring dispersion of liquids within each other as well as the incorporation of finely divided pigments, powders, etc. in liquids; for compounding of chemicals to speed up chemical reactions; the preparation of pharmaceutical compounds; the dispersion of bacteria in serums; the preparation of colloidal starch; the preparation of colloidal substances, such as starch, soda ash and sodium phosphate in water; the preparation of lithographic inks, printing inks, paints, colored lacquers, etc.

A further object is to supply a machine for such purposes having a stator combined with a rotor which is adjustable relatively thereto at all times whether the machine is in motion or not. With the foregoing objects outlined and with other objects in view which will appear as the description proceeds, the invention consists in the novel features hereinafter described in detail, illustrated in the accompanying drawings, and more particularly pointed out in the appended claims.

In the drawings:

Fig. 1 is a diametrical sectional view partly in elevation of one-half of the machine.

Fig. 2 is a similar view of the other half.

Fig. 3 is a transverse vertical sectional view of the machine taken on the line 3—3 of Fig. 1.

Fig. 4 is a similar view of the machine taken on the line 4—4 of Fig. 1.

Fig. 5 is an end elevation of one end of the machine and Fig. 6 is a similar view of the opposite end of the machine.

Referring to the drawings, 7 designates a hollow cylinder having a small portion 8 and a larger portion 9 with an internal annular shoulder 10 arranged at the line of the juncture.

The ends of the cylinder are closed by plates 11 and 12, secured to the ends of the cylinder by any suitable means, such as screws 13 so as to provide a fluid-tight structure.

A rotatable shaft 14 extends axially through the cylinder and through the hubs 15 of the end plates; each hub forming a chamber in which packing rings 16 are arranged and held com-

pressed by glands 17, screwed into the hubs of the end plates.

The end plate 11 is provided with an external extension 18 forming a support for a bearing structure 19 including an anti-friction bearing 5 20 in which the shaft is axially and rotatably movable.

The shaft may be driven by any suitable means connected with its end portion 21.

The end plate 12 is also provided with an external extension 22, a portion of which forms a hollow cylinder 23, longitudinally slit at 24. Where the slit is positioned, the cylinder 23 is provided with internal screw threaded ears 25 to cooperate with a screw 26 provided with a handle 27. Movement of the handle by the operator causes, through the instrumentality of the screw threads, the slit portions of the cylinder to move toward or away from one another. This is for the purpose of locking a cup 28 to the cylinder or for loosening the cup to allow it to be rotated. The cup has a threaded connection with the cylinder as shown at 29 and is provided with a hand wheel 30 to facilitate the turning of the cup by the operator. 25

Oppositely disposed anti-friction bearings 31 and 32 preferably of the thrust type are positioned in the cup and they are retained in place by a hollow plug 33; the latter being screwed into the cup at 34 and closing its open end. An end 30 of the shaft extends into the cup through packing means 35, and a nut 36 and shoulder 37 on the shaft lock the inner race rings 38 to the shaft so that the shaft will be forced to move endwise whenever the hand wheel 30 is rotated. 35

A rotor 39 is positioned on and rotates with the shaft, and such rotor preferably consists of a tube 40, keyed to the shaft at 41 and held against axial movement relatively to the shaft by means of nuts 42 and 43 which have threaded 40 engagement with the shaft.

A series of imperforate annular flanges 44, 45, 46 and 47 of progressively increasing diameters, from the end plate 11 toward the end plate 12, are rigidly united with and project outwardly 45 from the tube 40. A series of tubular walls 48, 49, 50 and 51 are respectively integral with the flanges 44, 45, 46 and 47. Each flange and its associated wall forms a cup, the wall of which is provided with lengthwise slots 52, 53, 54 50 and 55.

The wall 48 is of cylindrical form and is coaxial with the axis of the shaft while the walls 49, 50 and 51 flare toward the end plate 12 and are of progressively increasing diameters. Each 55

of the walls 49, 50 and 51 is also provided at the mouth of the cup with an imperforate annular inwardly extending flange 56 which function as baffles to cause fluid entering their associated 5 cups to travel inwardly toward the tube 40 before entering the cups.

A stator 57 is positioned in the cylinder 7 between such cylinder and the rotor, and such stator is of tubular form having portions 58, 59, 10 60 and 61 conforming to the external shape of the walls 48, 49, 50 and 51 and arranged in close proximity to the external surfaces of these walls.

The stator is also provided with lengthwise slots 62, 63, 64 and 65, and it will be obvious 15 that the distance between the slots of the rotor and the slots of the stator can be varied by turning the wheel 30.

The stator tube is held in position by the end plates 11 and 12 against which it abuts, and annular imperforate baffles 66, 67, 68 and 69 which 20 are arranged in spaced relation between the cylinder 7 and the stator, divide such space into a series of annular chambers 10, 11, 12 and 13. Ports 70a place the chambers 70-73 in communication with the interior of the rotor. The baffles 66-69 may be fixed to the stator, and when the 25 stator is introduced into the cylinder 7 through the end closed by the plate 12, the baffle 68 will come into engagement with the shoulder 10 so as 30 to stabilize the stator.

An inlet 74 leads into the cylinder near the plate 11 and discharges into an annular chamber 15, and fluid introduced in this way passes through slots 76 in the stator before entering 35 the first cup 44, 48. It will then travel in zig-zag paths through the slots in the cups and stator, and of course, will be constrained to move in this way due to the baffles 66, 67, 56, 68 and 69. When the fluid finally reaches the chamber 73 40 it can pass through slots 11 in the stator and eventually be discharged through an outlet nipple 78 positioned near the end plate 12.

In order that the temperature of the fluid being treated may be regulated, the cylinder 7 is surrounded by a jacket 79 so as to form an annular chamber 80 between the cylinder and jacket. A heating or cooling fluid can be introduced into such chamber through inlet nipple 81 and be discharged through an outlet nipple 82.

As best shown in Fig. 3, the slots 52-55 of the rotor are of V-shape with the points of the V's directed counter-clockwise, and the slots 62-65 of the stator are of similar shape with the points directed in a clockwise direction. In other words, 55 the V-shaped slots of one are directed in a direction opposite to the slots of the other so that fluid passing through the slots is subjected to violent impacts.

In my pending application Serial No. 196,780, 60 I have disclosed V-shaped slots arranged in discs positioned at right angles to the axis of the shaft of the rotor with the flow of liquid parallel to such axis. In the present invention with the V slots cut in the walls of the cups and the stator tube, the flow of the liquid through the slots is 65 at right angles to the axis of the shaft instead of parallel, and the motion is imparted to the liquid by the slots being substantially parallel to the axis of the shaft. The same principle of impact and shearing takes place in this improved 70 design, i. e., the liquid coming into each rotating cup is forced at right angles to the axis of the shaft out into the V-slots of the stator and in so doing is reversed in direction twice. In other 75 words, the slots of the rotor cup act to scoop

the liquid and then to cause it to impact at the angle of the slots and to then reverse the direction of flow before the fluid enters the inlet of the slots of the stator in reverse direction and, of course, each slot of the stator causes the fluid to reverse its direction before it is discharged from such slot.

Efforts in the past have utilized rotating surfaces where the relation of the speed of the respective surfaces was high. Dispersion by the method disclosed herein incorporates an entirely different principle. Instead of depending upon smashing into the solution with a rotating element and changing the direction of flow by impedance of either an oppositely rotating member or a stationary one, this principle incorporates the theory that the liquid is trying to catch up or build up the same velocity as the passageway through the rotating cylinder. This is practically impossible because the rate of feed or flow of the liquid through the slots is slower than the velocity of the cylinder through which the slots are cut. Therefore, there is a difference in velocity or ratio of speed between the liquid and the slot, and as the only point of outlet for the liquid is through the slot of the stator, liquid passing through the rotor is forced to be "stretched", sub-divided and sheared before a successful escape is possible. The velocities are slowed down from each stage or zone of the machine and speeded up again in the succeeding zone as the diameter of the rotating cups and the diameter of the rotor wall increases. The relative velocity progressively builds up because no more liquid can be discharged from the outlet 78 than is admitted through the inlet 74. This has a tendency, because of increased centrifugal force, to stretch the liquid further, or that being impossible, to increase its velocity and handle smaller quantities per slot in the larger diameters 40 of the rotor and stator. As the leading points of the discharge of the slots in the rotor can be moved to or from the leading edges of the slots in the stator, it can be readily understood that if particles are of larger size than can easily 45 pass through the clearance between the rotor and stator, they will be crushed, cut in two or otherwise deformed during the period of time of passage between the two members.

This principle is very important especially 50 when incorporating finely divided solid material into substances such as oil or colloidal mixtures of starch or the admixture of carbon black, antimony oxide, selenium or titanium oxide in rubber which has been dissolved in a solvent such 55 as benzene.

It is also important to break down the yeast cell during the fermentation period in the manufacture of beer so that the core or center of the yeast cell is exposed to the solution. This problem requires extremely fine dispersion of the smashing of the yeast cell in order to speed up the period of manufacture and to smash or break up the yeast cells to increase the rate of reaction. As these yeast cells are microscopic 65 in size and are floating in a liquid body of very low viscosity, the reaction is dependent upon the speed at point of transfer in order to break down the maximum number of cells per unit of time.

This mill has the characteristics of producing 70 colloidal mixtures and emulsions of widely different types of material such as oil and water, cut back rubber and water, residual pitches, wet starch cellulose in the liquid phase, etc., without the use of emulsifying agents to produce sta- 75

bilized non-segregating mixtures. These emulsions become stable because the component elements become surrounded with minute microscopic films around the individual globules and due to the difference in superficial tension have sufficient strength to remain in the stabilized form.

Practice in the past has demanded the use of emulsifying agents in order to stabilize emulsions. The physical reactions taking place within the mill herein described disperse and subdivide the various elements so finely that they remain in the stabilized condition without the use of emulsifiers. Most of the emulsifying agents have some chemical reaction upon substances to be emulsified and in many instances this is undesirable because it destroys the characteristic of the end product.

Chemical reactions can be speeded up because if a solid is to be dissolved by an acid or alkali the more finely dispersed the solvent is among the matter to be dissolved the more rapid the reaction can take place. This is due to the fact that the maximum amount of surface of the solid is exposed to the maximum amount of solvent to be used in a unit of time. It is also possible with mills of this type to put into the solution such products as liver like rubber in the presence of its solvents such as solvent naphtha, benzene or the like, in a very short period of time because of the rapid dispersion and dissemination due to the subdividing of the rubber substance so that a large amount of solvent can attack a smaller amount of jelly like rubber.

The operative condition may require that there be a minimum of $\frac{1}{1000}$ of an inch clearance between the outer face of the rotor and the inner surface of the stator, as the machine depends upon the media being transformed into a colloidal mixture or final form of dispersion for lubrication. My design is unique in that the machine causes very fine dispersion of substances of different viscosity because it is adjustable and its speed can be varied from zero to as high as 15,000 R. P. M. dependent upon the class of work to be done. It is considered important that such a machine be adjustable to compensate for different characteristics of material handled as well as wear on the machine.

I wish it particularly understood that my improved mill herein described and illustrated is in the form which I desire to construct it and that changes and variations may be made as may be convenient or desirable without departing from the salient features of my invention, and I therefore intend the following claims to cover such modifications as naturally fall within the lines of the invention.

What I claim and desire to secure by Letters Patent is:

1. In a machine of the character described, a rotor member provided with an annular wall having slots extending lengthwise thereof and of substantially V shape from the inner surface of the wall to the outer surface thereof, the plane of the V's of said slots being perpendicular to the axis of rotation of the rotor and a stator member having an annular wall arranged in close proximity to the wall of the rotor member, the wall of the stator member being also provided with slots opposed to the slots of the rotor member and of irregular shape from the inner surface of the annular wall of the stator member to the outer surface of such wall.

2. In a machine of the character described,

a rotor member provided with an annular wall having slots extending lengthwise thereof and of substantially V shape from the inner surface of the wall to the outer surface thereof, the plane of the V's of said slots being perpendicular to the axis of rotation of the rotor and a stator member having an elongated annular wall surrounding the rotor wall and arranged in close proximity to the latter, the wall of the stator member being also provided with slots opposed to the slots of the rotor member and of irregular shape from the inner surface of the annular wall of the stator member to the outer surface of such wall.

3. A machine of the character described a rotor member provided with an annular wall having slots extending lengthwise thereof, each slot having opposite walls of substantially V-shape to form a V-shape passageway through the wall extending from its inner to its outer surface, and a stator member having an annular wall arranged in close proximity to the wall of the rotor member, the wall of the stator member being also provided with slots opposed to the slots of the rotor member, the opposite walls of each slot of the stator being of substantially V-shape and forming passageways through the stator member with the points of the V's of the stator extending in a direction opposite to the points of the V's of the slots of the rotor, the plane of the V's of said slots being perpendicular to the axis of rotation of the rotor.

4. In a machine of the character described, a rotor member provided with an annular wall having slots extending lengthwise thereof, and a stator member having an annular wall arranged in close proximity to the walls of the rotor member, said walls being provided with opposed lengthwise slots, the walls of each slot being of V-shape and the points of the V's of the rotor wall being directly opposite to the points of the V's of the stator wall, the plane of the V's of said slots being perpendicular to the axis of rotation of the rotor.

5. In a machine of the character described, a rotor member provided with a flared annular wall, a stator member having an elongated flared annular wall arranged in close proximity to the wall of the rotor member and flared in the same direction, said walls being provided with opposed substantially V-shaped slots, the plane of the V's of said slots being perpendicular to the axis of rotation of the rotor and means for adjusting one of said members axially of the rotor and relatively to the other member to vary the clearance between said walls and the effective length of the slots.

6. In a machine of the character described, a rotor member provided with a flared annular wall, a stator member having a flared annular wall arranged in close proximity to the wall of the rotor member and flared in the same direction, said walls being provided with opposed slots, the walls of each slot being of V-shape from the inner surface to the outer surface of the wall and forming V-shaped passageways through the walls, the plane of the V's of said slots being perpendicular to the axis of rotation of the rotor and means for adjusting one of said members axially of the rotor and relatively to the other member to vary the clearance between said walls.

7. In a machine of the character described, a rotor having an annular wall including a flared portion, a stator having an elongated annular

- wall provided with a flared portion surrounding the flared portion of the wall of the rotor and arranged in close proximity to the latter, said flared portions being provided with opposed substantially V-shaped slots, the plane of the V's of said slots being perpendicular to the axis of rotation of the rotor and means for adjusting the rotor axially of the stator to vary the clearance between the flared portions of said walls.
8. In a machine of the character described, a rotor having an annular wall including a flared portion, a stator having an annular wall provided with a flared portion surrounding the flared portion of the wall of the rotor and arranged in close proximity to the latter, said flared portions being provided with opposed slots, and means for adjusting the rotor axially of the stator to vary the clearance between the flared portions of said walls, the walls of each of said slots being of V-shape from the inner surface to the outer surface of the wall through which it extends, the point of the V of each slot being positioned substantially midway between the inner and outer surfaces of the wall in which it is arranged.
9. In a machine of the character described, a rotor member having a cup provided with an annular wall, and a stator member having an annular wall arranged in close proximity to the wall of said cup, the walls being provided with opposed slots extending lengthwise thereof, the opposed walls of each slot being of substantially V shape from the inner surface to the outer surface of the wall in which the slot is arranged, the point of the V of each slot being positioned substantially midway between the inner and outer surfaces of the wall in which it is arranged.
10. In a machine of the character described, a rotor member having a cup provided with an annular wall, a stator member having an annular wall arranged in close proximity to the wall of said cup, the walls being provided with opposed slots extending lengthwise thereof, the opposed walls of each slot being of substantially V shape from the inner surface to the outer surface of the wall in which the slot is arranged, the point of the V of each slot being positioned substantially midway between the inner and outer surfaces of the wall in which it is arranged.
11. In mills for dispersion and mixing, a cylinder having closed ends, a shaft rotatably mounted in the cylinder, a rotor mounted on the shaft and provided with a series of cups arranged successively from end to end of the cylinder, each cup having an annular wall portion provided with slots extending lengthwise thereof, a stator surrounding the rotor and having an elongated tubular wall with its inner surface in close proximity to the wall portions of the cups, the wall of the stator having slots opposed to the slots of the wall portions of the cups of the rotor, means for admitting a fluid into one end portion of the cylinder and for discharging it from the opposite end of the cylinder, and baffles in the cylinder for causing the fluid in passing through the cylinder to travel successively through the slots of the cups and stator.
12. In a machine for dispersion and mixing, a cylinder having closed ends, a shaft rotatably mounted in the cylinder, a rotor mounted on the shaft and provided with a series of cups arranged successively from end to end of the cylinder, each cup having an annular wall portion provided with slots extending lengthwise thereof, a stator surrounding the rotor and having
- mounted in the cylinder, a rotor mounted on the shaft and provided with a series of cups arranged successively from end to end of the cylinder, each cup having an annular wall portion provided with slots extending lengthwise thereof, a stator surrounding the rotor and having an annular wall with its inner surface in close proximity to the wall portions of the cups, the wall of the stator having slots opposed to the slots of the wall portions of the cups of the rotor, means for admitting a fluid into one end portion of the cylinder and for discharging it from the opposite end of the cylinder, and baffles in the cylinder for causing the fluid in passing through the cylinder to travel successively through the slots of the cups and stator, opposed walls of each slot of the wall portion of one of the cups being of irregular shape from the inner surface to the outer surface of such wall.
13. In a machine of the character described, a cylinder having closed ends, a shaft rotatably mounted in the cylinder, a rotor mounted on the shaft and provided with a series of cups arranged successively from end to end of the cylinder, each cup having an annular wall portion provided with slots extending lengthwise thereof, a stator surrounding the rotor and having an annular wall with its inner surface in close proximity to the wall portions of the cups, the wall of the stator having slots opposed to the slots of the wall portions of the cups of the rotor, means for admitting a fluid into one end portion of the cylinder and for discharging it from the opposite end of the cylinder, and baffles in the cylinder for causing the fluid in passing through the cylinder to travel successively through the slots of the cups and stator, opposed walls of each slot of the wall portion of one of the cups being of V-shape and forming V-shaped passageways extending from the inner surface of said wall portion to its outer surface, the point of the V of each slot being positioned substantially midway between the inner and outer surfaces of the wall in which it is arranged.
14. In a machine for dispersion and mixing, a cylinder having closed ends, a shaft rotatably mounted in the cylinder, a rotor mounted on the shaft and provided with a series of cups arranged successively from end to end of the cylinder, each cup having an annular wall portion provided with slots extending lengthwise thereof, a stator surrounding the rotor and having an annular wall with its inner surface in close proximity to the wall portions of the cups, the wall of the stator having slots opposed to the slots of the wall portions of the cups of the rotor, means for admitting a fluid into one end portion of the cylinder and for discharging it from the opposite end of the cylinder, and baffles in the cylinder for causing the fluid in passing through the cylinder to travel successively through the slots of the cups and stator, opposed walls of some of the slots of the stator being of irregular shape from the inner surface of the wall of the stator to the outer surface of such wall.
15. In a machine of the character described, a cylinder having closed ends, a shaft rotatably mounted in the cylinder, a rotor mounted on the shaft and provided with a series of cups arranged successively from end to end of the cylinder, each cup having an annular wall portion provided with slots extending lengthwise thereof, a stator surrounding the rotor and having

- an annular wall with its inner surface in close proximity to the wall portions of the cups, the wall of the stator having slots opposed to the slots of the wall portions of the cups of the rotor, means for admitting a fluid into one end portion of the cylinder and for discharging it from the opposite end of the cylinder, and baffles in the cylinder for causing the fluid in passing through the cylinder to travel successively 5 through the slots of the cups and stator, each of said slots forming a V-shape passageway extending from the inner surface to the outer surface of the wall in which the slot is arranged, the point of the V of each slot being positioned substantially midway between the inner and outer surfaces of the wall in which it is arranged.
16. In a machine for dispersion and mixing, a cylinder having closed ends, a shaft rotatably mounted in the cylinder, a rotor mounted on the shaft and provided with a series of cups arranged successively from end to end of the cylinder, each cup having an annular wall portion provided with slots extending lengthwise thereof, a stator surrounding the rotor and having an annular wall with its inner surface in close proximity to the wall portions of the cups, the wall of the stator having slots opposed to the slots of the wall portions of the cups of the rotor, means for admitting a fluid into one end 10 portion of the cylinder and for discharging it from the opposite end of the cylinder, and baffles in the cylinder for causing the fluid in passing through the cylinder to travel successively through the slots of the cups and stator, said wall portions of the cups being flared in the direction toward the outlet of the cylinder and progressively increasing in size, the wall of the stator along such wall portions of the cups conforming in shape thereto, and means for moving one of said members relatively to the other to vary the clearance between the flared wall portions of the cups and the wall of the stator.
17. In a machine of the character described, a cylinder having closed ends, a shaft rotatably mounted in the cylinder, a rotor mounted on the shaft and provided with a series of cups arranged successively from end to end of the cylinder, each cup having an annular wall portion provided with slots extending lengthwise thereof, a stator surrounding the rotor and having an annular wall with its inner surface in close proximity to the wall portions of the cups, the wall of the stator having slots opposed to the slots of the wall portions of the cups of the rotor, means for admitting a fluid into one end portion of the cylinder and for discharging it from the opposite end of the cylinder, baffles in the cylinder for causing the fluid in passing through the cylinder to travel successively through the slots of the cups and stator, said wall portions of the cups being flared in the direction toward the outlet of the cylinder and progressively increasing in size, the wall of the stator along such wall portions of the cups conforming in shape thereto, means for moving one of said members relatively to the other to vary the clearance between the flared wall portions of the cups and the wall of the stator, the last-mentioned means comprising an extension at one end of the cylinder, a cup adjustably mounted on said extension, an anti-friction bearing arranged in the last-mentioned cup and in which a portion of the shaft is journalled, and means for constraining the shaft and rotor to move axially with said cup.
18. An apparatus for dispersion and mixing, comprising a hollow cylinder, plates closing the ends of the cylinder, a rotatable shaft extending through the cylinder, a rotor mounted on the shaft and comprising a series of cups of progressively increasing size from one end of the cylinder toward the other, means for introducing a fluid into the end of the cylinder where the smallest cup is arranged, means for discharging such fluid from the end portion of the cylinder where the largest cup is arranged, each of said cups being provided with a wall portion and such wall portions flaring toward the outlet end of the cylinder from the first cup to the last one of the series, an elongated tubular stator arranged in the cylinder and surrounding the rotor, the wall portion of each cup and the stator being provided with opposed slots through which the fluid can flow through a cup and then through the wall of the stator, and means in the cylinder 10 for constraining fluid entering the interior to pass progressively through the wall portions of the cups and several times through the stator before being discharged through said outlet.
19. An apparatus of the character described, comprising a hollow cylinder, plates closing the ends of the cylinder, a rotatable shaft extending through the cylinder, a rotor mounted on the shaft and comprising a series of cups of progressively increasing size from one end of the cylinder toward the other, means for introducing a fluid into the end of the cylinder where the smallest cup is arranged, means for discharging such fluid from the end portion of the cylinder where the largest cup is arranged, each of said 15 cups being provided with a wall portion and such wall portions flaring toward the outlet end of the cylinder from the first cup to the last one of the series, a stator arranged in the cylinder and surrounding the rotor, the wall portion of each cup and the stator being provided with opposed slots through which the fluid can flow through a cup and then through the wall of the stator, means in the cylinder for constraining fluid entering the interior to pass progressively 20 through the wall portions of the cups and several times through the stator before being discharged through said outlet, and means forming a bearing for said shaft and adjustable axially of the shaft for moving the rotor lengthwise relatively to the stator for varying the clearance between said flared wall portions of the cups and the wall of the stator.
20. In a machine of the character described, a rotor member provided with an annular wall 25 having slots extending lengthwise thereof and of substantially V shape from the inner surface of the wall to the outer surface thereof, a stator member having an annular wall arranged in close proximity to the wall of the rotor member, the wall of the stator member being also provided with slots opposed to the slots of the rotor member and of substantially V shape from the inner surface of the annular wall of the stator member to the outer surface of such wall, 30 the point of the V of each slot being positioned substantially midway between the inner and outer surfaces of the wall in which it is arranged means for axially adjusting one of said members relatively to the other, the edges of the walls of 35 the slots being of such configuration as to remain parallel to each other regardless of the operative position of the adjustable member relatively to the other member.
21. In a machine of the character described, 40

a cylinder having closed ends, a shaft rotatably mounted in the cylinder, an elongated rotor mounted on the shaft and provided with a series of cups arranged successively from end to end of the cylinder, each cup having an annular wall portion provided with slots extending lengthwise thereof, the opposed walls of each slot being of substantially V-shape from the inner surface to the outer surface of the wall portion in which it is arranged, a stator surrounding the rotor and having an elongated tubular wall with its inner surface in close proximity to the wall portions of the cups, the wall of the stator having slots opposed to the slots of the wall portions of the cups of the rotor, the walls

of each slot of the stator being of substantially V-shape with the points of the V's pointing directly opposite to the points of the V's of the slots of the rotor, the point of the V of each slot being positioned substantially midway between the inner and outer surfaces of the wall in which it is arranged means for admitting a fluid into one end portion of the cylinder and for discharging it from opposite end of the cylinder, and baffles in the cylinder for causing the fluid in passing through the cylinder to travel in a zig-zag path successively through the slots of the cups and stator. 5

MARVIN W. DITTO. 10 15
